UNITED STATES PATENT OFFICE.

HARRY C. GAMMETER, OF CLEVELAND, OHIO, ASSIGNEE TO THE AMERICAN MULTIGRAPH COMPANY, OF CLEVELAND, OHIO, A CORPORATION OF OHIO.

REMOVABLE FORM-HOLDER FOR PRINTING-MACHINES.

1,122,728.

Specification of Letters Patent.

Patented Dec. 29, 1914.

Original application filed January 3, 1910, Serial No. 535,962. Divided and this application filed April 20, 1914. Serial No. 833,051.

To all whom it may concern:

Be it known that I, HARRY C. GAMMETER, a citizen of the United States, residing at Cleveland, in the county of Cuyahoga and State of Ohio, have invented a certain new and useful Improvement in Removable Form-Holders for Printing-Machines, of which the following is a full, clear, and exact description, reference being had to the accompanying drawings.

My Patent No. 1,094,065 shows, describes and claims a rotary printing machine having a removable segment provided with rails for holding lines of individual type, there being suitable means for locking the segment to the shaft of a skeleton drum, which, with the segment, constitutes a rotary printing drum coacting with a suitable platen.

In the present invention, I have provided improved means for holding the segment on the skeleton drum. This improved means is shown in my application No. 535,962, filed January 3rd, 1910, of which the present application is a division.

The present invention is hereinafter more fully explained and its essential characteristics are set out in the claims.

In the drawings, Figure 1 is a front elevation of a rotary printing machine equipped with my removable segment and improved holding means; Fig. 2 is a vertical transverse section of the same.

Referring to the drawings, the frame of my machine consists of a base 10 and vertical end plates 11 and 12. Mounted in these end plates is a rotary shaft 13 provided with suitable means for rotating it, as, for example, the crank 14. Rigid on this shaft are a pair of end members 15 and 16, which are in the form of wheels, rings or spiders. Rigid with the wheel 16 is a gear 17 which meshes with a gear 19, connected with the platen 18.

Resting on rotary supports or wheels 15 and 16 is the segment 20 provided with longitudinal rails 21, some of which are omitted in Fig. 2 for clearness of illustration. Each rail has an overhanging edge so that it is adapted to coöperate with its neighbor to confine a line of type 24 grooved on its opposite sides.

The purpose of the present invention is to provide simple and effective means for locking the segment to the skeleton drum

consisting of a shaft 13 and end members 15 and 16. I accomplish this by providing one or more sheet metal spring hooks 30, which are mounted on a rod 31 carried by transverse webs 22 of the segment, and are formed with hooked ends 32 adapted to spring around the shaft 13.

In installing my segment, it is only necessary to place it on the end members 15 and 16, and, with a suitable pressure of the operator's hand, spring the hooks 32 about the shaft. The bent portion of the spring 30, as shown most clearly in Fig. 2, enables these springs to have their ends pass about the shaft, and, at the same time, provide suitable tension, when the segment is in place, to hold it properly on its seat. To unlock the segment it is only necessary to apply finger pressure on the curled end of the hooks 32, which frees them from the shaft, and the segment may then be lifted off. The end members 15 and 16 are preferably braced by tie rods 29 and the transverse webs 22 may be formed to substantially abut the tie rod, though the segments actually seat on the end members 15 and 16.

The printing drum, when the segment is in place, it will be seen, is open for substantially half of the circumference. In this half are mounted the two ribbon spools 40 and 41, which are suitably journaled in the end members 15 and 16. These spools carry an inking ribbon 42, which extends across guide rods or rollers 43 and about the segment and supply the ink for the impression.

Having thus described my invention, what I claim is:

1. The combination of a rotary member comprising a shaft and a pair of end rings, a removable typeholding segment adapted to seat on such rings, and a spring metal hook carried by the segment and adapted to engage the shaft.

2. The combination of a rotary member comprising a shaft and a pair of end rings, a removable segment adapted to seat on such rings, said segment having a plurality of internal webs, a rod carried by such webs, and a hook carried by the rod and adapted to engage the shaft.

3. The combination of a shaft, a pair of supports carried thereby, a removable typeholding segment seating on such support and having an internal web extending be-

tween the supports, a longitudinal rod carried by said web, and a spring hook mounted on said rod and adapted to engage said shaft between said supports.

5 4. The combination of a shaft, a pair of ring-like members carried thereby, a segment adapted to seat on such ring-like members, typeholding means carried by said segment, said segment having a plurality of
10 transverse internal webs extending between the ring-like members, a rod carried by said

webs, and a sheet metal spring hook curled at one end around said rod and formed at the other end with a hook portion adapted to spring over said shaft.

15

In testimony whereof, I hereunto affix my signature in the presence of two witnesses.

HARRY C. GAMMETER.
